United States Patent Office

Des. 221,560
Patented Aug. 24, 1971

221,560

ROOM DIVIDER

John H. Jordan, Jr., 8124 S. Crandon Ave.,
Chicago, Ill. 60617

Filed Feb. 6, 1970, Ser. No. 21,312

Term of patent 14 years

Int. Cl. D6—99

U.S. Cl. D33—1

FIG. 2.

FIG. 3.

FIG. 1.

FIG. 4.

FIG. 1 is an elevational view from the front of a room divider showing my new design;

FIG. 2 is a plan view of the room divider;

FIG. 3 is a side elevation of the room divider taken from the left side; and

FIG. 4 is a side elevation of the room divider taken from the right side.

The side of the room divider not shown is a mirror image of the side shown.

I claim:

The ornamental design for a room divider, as shown and described.
